UNITED STATES PATENT OFFICE

HUGH G. BUCHAN, OF PHILADELPHIA, PENNSYLVANIA

BINDER

Application filed August 14, 1929. Serial No. 385,797.

This invention relates to a pamphlet binder of that type in which a plurality of catalogues or trade journals, or books may be removably confined. The invention concerns itself more directly with the means for supporting the pamphlets and involves a structure which can be swung beyond one end of the binder for the purpose of assembling the pamphlets.

10 The invention comprises the novel structure and combination of parts hereinafter described and more particularly pointed out and defined in the appended claims.

In the accompanying drawings which illustrate a preferred form of this invention and in which similar reference numerals refer to similar features in the different views:

15 Figure 1 is an interior fragmentary plan view of the binder showing the pamphlet confining means in dotted lines in its swung-out position.

20 Figure 2 is a perspective view of the binder with a number of pamphlets confined therein.

25 Figure 3 is an enlarged fragmentary sectional view taken in a plane transverse of the pamphlet confining means.

30 Figure 4 is an enlarged sectional view taken upon the line IV—IV of Figure 3 looking in the direction of the arrows.

35 Figure 5 is a side elevational view of the pamphlet confining means.

In connection with this invention, there is shown a binder consisting of the side cover members 1 and a back member 2 as is usual

40 in the art. A pair of angle members 3 and 4 are secured along the lateral margin of the back 2 adjacent the upper end thereof as shown in Figures 1 and 3. These angle members have one flange attached to the back of

45 the binder with the other flange directed upwardly at right angles thereto. Upon the lower end of the binder, there is a U-shaped metal clip 5, which extends transversely of the back of the binder and is provided with

50 upstanding apertured ears 6. A U-shaped metal frame 7 is pivoted at the end of its arm upon the upstanding ears 6 by means of a rod 5^a which rod extends through the apertured portion of the ears 6 and connects the

55 ends of the arms of the frame 7. A rod 8 ex-

tends transversely of the upper end of the U-shaped frame, and the rods 5^a and 8 are adapted for slidably retaining the pamphlet holding bars 9. The frame member 7 is adapted to swing between the upstanding flanges of the angles 3 and 4 as shown in Figure 3.

60 Means are provided for releasably latching the upper end of the frame 7 between the angle members 3 and 4. While this means may assume any convenient form, in the present instance it has been illustrated as consisting of a pair of resilient metal strips 10 which extend through suitable keepers 11 struck from the upstanding flanges. The resilient strips 65 10 carry pintles 12 which are adapted for extending through apertures in the upstanding flanges of the angles 3 and 4 and through apertures in the U-shaped frame 7.

70 The resilient strips and pins 12 constitute latching means for latching the U-frame 7 in its operative position. When the resilient strips 10 are pulled outwardly as shown in dotted lines in Figure 1, the U-frame may be swung into the position shown in dotted lines 75 in Figure 1. In this dotted line position, the pamphlets may be readily suspended upon the supporting rod 9, and the frame may thus be swung over the cover and the pintles 12 upon the resilient strips 10 may be engaged 80 with the U-frame as is obvious. When the U-frame 7 has been swung into its dotted line position, the resilient strips 10 will of course snap back into their normal position. It is necessary to deflect them again before the 85 U-shaped frame 7 can be latched in its operative position.

90 From the foregoing structure, it will be obvious that a pamphlet binder has been provided which greatly facilitates the assembling or pamphlets thereof. Further, as these pamphlet supporting rods or wires are permanently attached to the rods 5 and 8, it is impossible for them to become loose or go astray.

95 I am aware that numerous details of construction may be varied through a wide range without departing from the principles of this invention, and I therefore do not purpose 100

limiting the patent granted, otherwise than necessitated by the prior art.

I claim as my invention.

1. A pamphlet binder comprising a back portion, a rod secured to one end of said back portion, a U-shaped frame having the ends of its arms pivoted to said rod and swingable toward and away from said back member, pamphlet-supporting means carried by said U-frame and said rod, and means for latching said U-shaped frame to said back member.
2. A pamphlet binder comprising a back portion, a rod secured to one end of said back portion, a U-shaped frame pivoted to said rod, a pair of angle members secured to the opposite end of said back portion, resilient latching members secured to said angle members, said U-shaped frame being swingable between said angle members, and means on said latch members for latching said U-shaped frame to said angle members.
3. A pamphlet binder comprising a cover member, a frame pivoted to one end of said cover member and swingable to a position within said cover member, pamphlet-confining means carried by said frame, and resilient means adapted to extend into the legs of said frame for latching said frame member within the cover member.
4. A pamphlet binder comprising a cover having a back portion, a frame pivoted to one end of said back portion, a pair of members having upstanding portions at the other end of said back portion for receiving said frame member therebetween, and means upon said upstanding portions for releasably latching said frame member thereto.
5. A pamphlet binder comprising a cover member having a back portion, a U-shaped frame pivoted at its open end to one end of said cover member, a pair of angle members on said cover member for receiving said U-shaped frame member therebetween, resilient latch members secured to said angle members and having pintles thereon, said angle members and U-shaped frame having apertures for receiving said pintles for latching said U-shaped frame member to said angle members.
6. A pamphlet binder comprising a back portion, a U-shaped frame pivoted to one end of said back portion, pamphlet supporting rods carried by said frame and means for removably latching said frame to the other end of said back portion.

In testimony whereof I have hereunto subscribed my name at Philadelphia, Philadelphia County, Pa.

HUGH G. BUCHAN.
